(57) **CLAIM**

The ornamental design for an antenna for wireless tag, as shown and described.

DESCRIPTION

1. Antenna for wireless tag

1.0 : Front surface view, the rear surface view being a mirror image thereof.

The portion illustrated with solid lines is the portion for which design registration is sought; the dashed lines shown in the drawings represent portions of the antenna for wireless tag that form no part of the claimed design; a rear surface view is omitted because it is a mirror image of the front surface view.
